UNITED STATES PATENT OFFICE.

WARREN W. HELLE, OF HINSDALE, ILLINOIS, ASSIGNOR TO STARITE MANUFACTURING COMPANY, OF CHICAGO, ILLINOIS, A CORPORATION OF ILLINOIS.

ROLLER AND FLEXIBLE SHEET.

1,272,338.

Specification of Letters Patent.

Patented July 9, 1918.

Application filed May 29, 1915. Serial No. 31,129.

To all whom it may concern:

Be it known that I, WARREN W. HELLE, a citizen of the United States, residing at Hinsdale, in the county of DuPage and State 5 of Illinois, have invented new and useful Improvements in Rollers and Flexible Sheets, of which the following is a full, clear, concise, and exact description, reference being had to the accompanying drawing, forming a part of this specification.

My invention relates to a flexible sheet and roller support therefor, and more specifically to such a device used as a telephone directory and provided with means whereby 15 it may be secured to the mouth-piece of the telephone.

One of the objects of my invention is to provide a device of this character which shall be simple in construction, neat in appearance and efficient in use.

Further objects will appear from the detailed description to follow taken in connection with the appended claims.

In the accompanying drawings in which 25 I have shown one embodiment of my invention—

Figure 1 is a front elevation showing the directory in position on the telephone.

Fig. 2 is a side elevation of the parts 30 shown in Fig. 1;

Fig. 3 is a vertical axial section through the roller showing the manner in which the roller is held in place in the bearing caps, and the bearing caps in the frame, and showing the manner in which the rewinding spring is secured to the bearing cap and to the roller;

Fig. 4 is a section on the line 4—4 of Fig. 3 showing the manner in which the flexible 40 strip is secured to the roller;

Fig. 5 is a perspective view of the bar by which the spring is connected to the roller;

Fig. 6 is a perspective view of the roller.

Referring now to the drawing in detail 45 I have shown my improved device in connection with a telephone comprising a standard 10, a transmitter casing 11 and a mouth-piece 12. The device itself comprises a roller supporting member 13, a roller 14, and a flexible sheet 15 secured to the roller. The supporting member 13 comprises a ring portion 16 which loosely surrounds the mouth-piece 12 of the telephone, downwardly extending portions 17 which are held

in proper position relative to each other by 55 means of a strip 17^a bent therearound, outwardly extending portions 18, forwardly extending portions 18^a and ring portions 19 in which the bearing caps 20 and 21 for the roller are secured. These bearing caps 20 60 and 21 fit somewhat tightly in the ring portions 19 so that they are held securely and prevented from rotation. The ring portions 19 may be somewhat springy and yield 65 slightly when the caps are fitted in place. The cap 20 comprises a dished portion 22 to receive the end of the roller, and a flange portion 23 which engages the ring portion 19 to position the cap with respect thereto.

The cap 21 comprises a dished portion 24 70 to receive the other end of the roller 14 and a flange portion 25 to engage one of the ring portions 19. The roller 14 is slotted or split longitudinally, as shown at 26, to permit the flexible sheet 15 to be easily secured thereto, this flexible sheet having a 75 small rod 27 secured thereto at its upper end; the rod 27 with a portion of the flexible sheet 15 lying within the roller 14, as shown in Fig. 4, and the flexible sheet extending 80 out through the slot 26.

In assembling the roller and flexible sheet the edge of the sheet is slipped into the slot 26 at one end of the roller, the end of the rod 27 lying within the roller; and the sheet 85 and rod are then slipped over sidewise until the rod 27 is entirely within the roller 14. The rod 27 is large enough so that it will not slip out through the slot 26.

A rod 28 is secured to the lower edge of 90 the sheet 15 and is provided with a ring portion 29 by means of which the sheet may be unwound from the roller. The means for rewinding the sheet 15 on the roller after it has been unwound therefrom comprise a 95 bar 30 secured to the roller and a spring 31 secured to the bar and surrounding it and having one end 32 secured beneath struck-up portions 33 of the cap 21. The bar 30 is provided with wing portions 34 about which 100 the end of the spring 31 is wrapped to secure the spring and bar together, and is also provided with lugs 35 which fit within recesses 36 in the roller to prevent relative rotation between the bar 30 and the roller. 105 The outer edges of the wings 34 engage snugly within the roller 14 to aid in positioning the bar with respect to the roller.

The flexible sheet 15 may be ruled to provide a column 38 for the names which are to be placed on the directory, a column 39 for the exchange, and a column 40 for the 5 telephone number.

The use and operation of my improved device is as follows: To secure the device in place on the telephone the mouth-piece 12 is unscrewed from the transmitter casing 10 and the ring portion 16 is slipped over the mouth-piece which is then screwed back in place. When it is desired to look up a number on the directory the sheet 15 is unwound from the roller by pulling downwardly 15 on the ring 29. It will be noted that because of the fact that the ring portion 16 fits somewhat loosely on the mouth-piece 12 that a sidewise pull on the sheet 15 when it is being unwound will not cause the edges 20 of the sheet to be rubbed and worn against the flanges 23 and 25, as the supporting member 13 will swivel about the mouth-piece 12 so that the sheet 15 will unwind properly.

In assembling the roller 14, bar 30, spring 31 and cap 21, the bar 30, spring 31 and cap 21 may first be assembled, after which the bar 30 and spring 31 may be slipped within the roller 14, the slot 26 being wide enough 30 so that when sprung a little the wing portions 34 can be slipped between the edges of the slot 26. The wings 34 are slipped along until they come out at the other end of the roller 14 when they may be rotated a quarter turn to permit the lugs 25 to seat in the recesses 36. The sheet 15 is then secured in place as described above. After these parts 35 have been assembled the cap 20 is slipped over the end of the roller, and the caps 20 and 21 are fitted within the ring portion 19 of the supporting member 13, the ring portions 19 being sprung outwardly slightly to 40 permit the caps to be put in place.

When the sheet 15 is unwound from the 45 roller the latter rotates within the bearing caps 20 and 21.

It will be noted that I have provided a device which is extremely simple in construction, and which may be made almost 50 entirely from stamped sheet metal and bent wire parts.

Having thus described my invention what I claim as new and desire to secure by Letters Patent is:

- 55 1. In a device of the character described, a roller formed of sheet material and of uniform diameter throughout its length, a flexible sheet secured thereto and means for rotatably supporting said roller comprising a bearing cap surrounding one end of said roller and engaging the periphery thereof.
- 60 2. In a device of the character described, a roller, a flexible sheet secured thereto, means for rotatably supporting said roller comprising a bearing cap surrounding one

end of said roller, and a member having an opening therein in which said bearing cap fits snugly.

3. In a device of the character described, a roller formed of sheet material and of uniform diameter throughout its length, a flexible sheet secured thereto and means for rotatably supporting said roller comprising a bearing cap surrounding one end of said roller and engaging the periphery thereof, 75 said cap being provided with a flange for guiding the flexible sheet.

4. In a device of the character described, a roller, a flexible sheet secured thereto, means for rotatably supporting said roller 80 comprising a bearing cap surrounding one end of said roller, and a member having an opening therein in which said bearing cap fits snugly, said cap being provided with outwardly extending means for engaging 85 said member to position the cap with respect thereto.

5. In a device of the character described, a roller, a flexible sheet secured thereto, 90 means for rotatably supporting said roller comprising a bearing cap surrounding one end of said roller, and a wire loop in which said cap fits snugly.

6. In a device of the character described, a roller, a flexible sheet secured thereto, 95 means for rotatably supporting said roller comprising a bearing cap surrounding one end of said roller, and a wire member comprising a loop in which said cap fits snugly, and a loop for hanging up the device, said 100 loops being formed from a single integral piece of wire.

7. In a device of the character described, a roller of uniform diameter throughout its length, a flexible sheet secured thereto, 105 means for rotatably supporting said roller comprising a bearing cap surrounding one end of said roller and engaging the periphery thereof, and a torsion spring having one end secured to said bearing cap and the 110 other end to said roller.

8. In a device of the character described, a hollow roller of uniform diameter throughout its length, a flexible sheet secured thereto, means for rotatably supporting said 115 roller comprising a bearing cap surrounding one end of said roller and engaging the periphery thereof, and a torsion spring having one end secured to said bearing cap and the other end to said roller and lying within 120 said roller.

9. In a device of the character described, a hollow roller, a flexible sheet secured thereto, means for rotatably supporting said 125 roller comprising a bearing cap, a bar located within said hollow roller and having one end connected thereto, and a coiled torsion spring surrounding said bar and having one end connected thereto and its other end connected to said bearing cap.

10. In a device of the character described, a hollow roller, a flexible sheet secured thereto, means for rotatably supporting said roller comprising a bearing cap, a bar located within said hollow roller and having one end connected thereto, and a coiled torsion spring surrounding said bar and having one end connected thereto and its other end connected to said bearing cap, said roller having a notch therein and said bar having 10 a lug engaging said notch.

In witness whereof, I have hereunto subscribed my name.

WARREN W. HELLE.
